(*) **Notice:** This patent is subject to a terminal disclaimer.

Naoyuki Senda, U.S. Appl. No. 29/497,469, filed Jul. 24, 2014,
Specification and Drawings.

(**) **Term:** 14 Years

Primary Examiner — Paula Greene

(21) **Appl. No.:** 29/498,844

(74) **Attorney, Agent, or Firm:** Nixon Peabody LLP;
Jeffrey L. Costellia

(22) **Filed:** Aug. 8, 2014

CLAIM

(30) **Foreign Application Priority Data**

I claim, the ornamental design for a portable information terminal, as shown and described.

Feb. 13, 2014 (JP) 2014-002832

DESCRIPTION

(51) **LOC (10) Cl.** 14-02

FIG. 1 is a front view of a portable information terminal showing my new design;

(52) **U.S. Cl.**

FIG. 2 is a rear view;

USPC D14/341

FIG. 3 is a right side view;

(58) **Field of Classification Search**

FIG. 4 is a left side view;

USPC ..... D14/345, 341, 138 AB, 138 G, 496, 331,
D14/440, 445, 501, 126, 127, 132, 202,
D14/203.4; 313/511; 361/679.01, 679.27,
361/749, 679.04, 679.03, 679.32, 679.11,
361/679.26; 455/575.1, 575.3, 566;
345/204, 173, 581, 156, 55, 168, 169;
349/58

FIG. 5 is a top view;

CPC G06F 1/16; G06F 1/1616

FIG. 6 is a bottom view;

See application file for complete search history.

FIG. 7 is a front view in which a flexible display is unfolded;

(56) **References Cited**

FIG. 8 is a rear view in which the flexible display is unfolded;

U.S. PATENT DOCUMENTS

FIG. 9 is a right side view in which the flexible display is unfolded;

3,121,884 A * 2/1964 Emery A47C 1/146
248/456

FIG. 10 is a left side view in which the flexible display is unfolded;

FIG. 11 is a top view in which the flexible display is unfolded;

FIG. 12 is a bottom view in which the flexible display is unfolded; and,

FIG. 13 is an enlarged sectional view taken from A-A' in FIG.

1 with the internal mechanisms omitted.

The portable information terminal is used in a state in which the flexible display is folded, unfolded or curved as necessary.

1 Claim, 7 Drawing Sheets
